ORE STRATIFYING AND CONCENTRATING MEANS

Ralph Sparks, Pecos, Tex.

Application May 3, 1951, Serial No. 224,308

3 Claims. (Cl. 209—443)

1

This invention relates to means for the classification of comminuted ores and analogous materials with respect to their relative density and the isolation of one of the so-classified density categories as an incident of the classification operation, and has as an object to provide improved means effective to attainment of the ends set forth.

A further object of the invention is to provide improved apparatus economically and efficiently operable to classify comminuted ores with respect to particle density and to isolate a selected density fraction of the so-classified material as an incident of the classifying operation.

A further object of the invention is to provide improved means for the extraction or recovery of values from comminuted natural ores.

A further object of the invention is to provide means operable to effect repetitious and progressive concentration of comminuted natural ores to ultimate recovery of a value fraction therefrom.

A further object of the invention is to provide improved means of vibrating table type adapted for the concentration of ores in either dry or wet pulp form.

A further object of the invention is to provide improved means of vibrating table type operable to classify and simultaneously separate comminuted ore material with reference to the relative density of the ore particles.

A further object of the invention is to provide improved means of vibrating table type adapted for the repetitious and progressive concentration of comminuted ore material.

A further object of the invention is to provide an improved construction and arrangement of elements constituting a vibrating table for the classification of material with respect to relative particle density.

A further object of the invention is to provide an improved construction and arrangement of elements constituting a selective-adjustable vibrating table characterized by means for the progressive concentration of material thereover.

A further object of the invention is to provide an improved construction and arrangement of elements constituting a vibrating table operable to stratify ore material with respect to particle density and to isolate a fraction of characteristic density from the material as an incident of its classifying operation.

With the foregoing and other objects in view, my invention consists in the nature and sequential relation of steps constituting a method, and

2

in the construction, arrangement, and combination of elements constituting apparatus, for the concentration of ores and analogous materials, all as hereinafter set forth, pointed out in my claims and illustrated by the accompanying drawing, in which—

which

Figure 1 is a schematic representation of typical means applicable to and in an arrangement effective for practice of my improved method, the 10 flow of material relative to the illustrated apparatus being indicated by arrows. Figure 2 is a typical diagram, or flow sheet, exemplifying the method characteristic of the arrangement according to Figure 1. Figure 3 is a side elevation 15 of a vibrating table assembly embodying the principles of the invention and effective for practice of the improved method, alternative positions to which certain of the table elements are adjustable being indicated by broken lines. Figure 20 4 is a top plan view of the apparatus according to Figure 3. Figure 5 is a transverse section taken substantially on the indicated line 5—5 of Figure 3. Figure 6 is a front, or discharge, end elevation of the organization according to Figure 3. 25 Figure 7 is a fragmentary, detail elevation of typical means for vibrantly actuating the table element of the apparatus shown in Figures 3-6. Figure 8 is a fragmentary, detail elevation, partly in section, of a table-mounting connection employed in the apparatus assembly illustrated. 30 Figure 9 is a fragmentary, detail isometric view of the front, or delivery end of the vibrating table included in the apparatus as illustrated. Figure 10 is a fragmentary, detail, side elevation, on a 35 relatively enlarged scale, of the table end shown in Figure 9. Figure 11 is a fragmentary, detail section, on the same scale as Figure 10, taken substantially on the indicated line 11—11 of Figure 9. Figure 12 is a conventionalized diagram of 40 the means and connections appropriate to effect table vibration through the agencies shown in Figure 7.

In the art and practice of ore dressing, it has long been recognized that the relative density of the grains or particles of an appropriately comminuted ore may be availed of for concentration of the ore with respect to its value content and for separation of values from the gangue of the ore. Among techniques applicable for utilization of such relative density differential with ore value concentrating and separating effect, it is well established that a comminuted ore fed and translated in suitable bed depth to and across a vibrating table may be induced to travel over the table and caused to progressively stratify

thereon, in direct reaction to appropriate vibratory characteristics of the table, in and as superposed horizontal courses and zones distinguished and characterized by constituent particle densities grading from a maximum adjacent the table surface and to a minimum in the uppermost course or zone of the bed. In a utilization and practical application of the principles and techniques just expressed, the instant invention is directed to a reorganization and extension of known practices constituting a novel and improved method for the concentration and separation of ore value components, and to the provision of novel and improved means operable for the practice of such method, as hereinafter elaborated.

The improved method as schematically shown in Figure 1 and diagrammatically represented by Figure 2 embraces and is applicable to but that phase or step of ore dressing wherein concentration and separation of particular ore components is accomplished, hence, for purposes of this description, discussion of preliminary ore dressing steps, such as crushing, grinding, picking, screening, and classifying, will be omitted and it will be assumed that the ore to be concentrated by the improved method and through the improved apparatus is comminuted to a substantial uniformity of fineness appropriate for purposes of the separatory treatment and in condition, either wet or dry, for delivery at a controlled rate to the receiving end of a vibrating table through a conventional ore feeding device.

While the improved method and novel apparatus hereinafter described are effectively applicable to the treatment of ground, or naturally granular, ores in either wet or dry condition, the advantages thereof are particularly manifest in the processing of dry ore material at or adjacent its source, hence it is only in relation to the processing of such dry materials that the improvements are hereinbelow discussed.

In the practice of the improved method as typically exemplified by Figures 1 and 2, the ore material to be concentrated is delivered in appropriately-ground condition to a conventional ore feeder 15 whereby it is fed at a suitable rate to the input, or receiving end of a plane, generally-horizontal table 16 mounted and actuated for vibration in a manner effective to translate the material along the table from the receiving and to the discharge end thereof and to stratify the material into superposed layers or zones of characteristic particle density as an incident of such translation; the stratum of greatest particle density naturally being the lowermost and hence in contact with or very closely adjacent the table upper surface. As the so agitated and translated material approaches the discharge end of the table 16 and the desired stratification thereof according to particle density is well developed, a significant feature of the invention is realized as and through horizontal plane separation of the stratified material bed accomplished as an incident of material translation along the table and by means effective to divert one of the so-separated horizontal bed fractions away from the table while the other fraction continues its travel along the table to and over the discharge end thereof. As represented by Figure 1, a lip 17 transversely of the table 16 and inwardly adjacent the table discharge end may be elevated relative to the plane of the table upper surface to define a throat through which a lower layer of stratified material from the bed under trans-

lation may be diverted in a depth or thickness corresponding to lip 17 elevation above the table plane and received in a side-discharge launder 18, or equivalent means for its segregation and direction, while the superincumbent depth of the bed material passes over said lip to and over the discharge end of the table, all in reaction to appropriately-conditioned vibration of the table 16.

When the improved method is applied to the separation and recovery of the higher density material constituents, as is customary practice in the concentration of ores carrying metallic values, the lip 17 is set at an elevation relative to the table such as will serve to slice away from the material bed that lower, horizontal layer within which the particles to be recovered have been stratified and hence will operate to divert such lower layer through the launder 18 and to further processing stages while the lighter material layers passing over said lip may be discharged from the table to waste or further processing. However, the method is equally applicable to the separation and recovery of lower density material constituents, when such a result is desired, since the lip 17 may be set to divide the material bed at an appropriate plane and the fraction diverted through the launder 18 may go to waste while the fraction delivered over the table discharge end may be conserved for use or further processing.

Since it is usually impractical and uneconomic to attempt definitive concentration of an ore in a single stage, the improved method contemplates and includes progressive and repetitious processing of successive ore concentrate fractions to desired ultimate recovery, it being feasible in many instances to take a first rough concentrate or fraction carrying all of the material constituents sought together with some of the undesired constituents and to progressively enrich such first concentrate by repetitious treatment thereof through the agency of the means first employed or through other and like means subsequent in the cycle of operations. Thus, as is clearly represented in Figures 1 and 2, the lip 17 may be set to divert a lower layer of the material bed containing all of the desired higher density value particles into the launder 18 while the gangue of lower density particles goes to waste over the table discharge end, the table 16 may be divided by means of an upstanding, longitudinally-disposed rib 19 into a wider surface area served by the feeder 15 and a narrower surface area 16' served by a feeder 15', the delivery of concentrate from the launder 18 may be routed to the feeder 15' and thence to the area 16' of the table, and an independent lip 17', in all operative respects the same as the lip 17, may be associated with the table area 16' to establish a throat serving an independent, side-delivery launder 18' for the segregation and direction of a second concentrate derived from the first concentrate as the latter is repassed over the table of its origin against an appropriate setting of the lip 17'. As is apparent, the lower density concentrate from the first stage of table 16 operation could be routed to reprocessing over the second stage of the table, instead of the higher density first stage concentrate, if such were desired, or, when expedient, either concentrate or fraction from the table 16 could be routed to a second like table, or to a succession of such tables, for consequent enrichment and reduction of bulk, all such being well within the contemplation and disclosure of the invention.

From the foregoing it should be apparent that the improved method of the invention is that technique or process of ore concentration which consists of stratifying the ground ore according to particle density as an incident and consequence of its translation in a bed of appropriate depth by and across a vibrating table and coincidentally isolating and diverting from the table a selected horizontal layer fraction of the so-stratified material, either in and as a single stage operation or in and as a multi-stage operation characterized by repetitious like processing of the concentrates to ultimately-desired enrichment.

A vibrating table construction and operative mounting suitable for practice of the improved method above set forth as applied to various materials is exemplified by Figures 3-12, inclusive, of the drawings. As shown, the table 16 is represented as a smooth, plane sheet of rigid material formed or provided with upstanding marginal flanges 20 along its spacedly-parallel long sides, a similar flange 21 closing between the said flanges 20 across the intake end of the table, and the rib 19 rising from the sheet between and in parallel relation with the flanges 20 to divide the sheet into a wider upper surface area designated as 16 and a narrower such area 16', it being manifest that the sheet constituting the operating areas of the table may be fabricated, reinforced, and braced in any particular manner to provide a rigid unit resistive of deformation during its use. Inwardly from the normal discharge end of the table the sheet areas 16 and 16' are transversely cut through, as at 22, and the edge so formed cooperates with the lips 17 and 17' of hingedly-adjustable panels 23 and 23', respectively, to constitute discharge throats of variable effective openings through which lower layers of the table charge may be diverted as an incident of charge translation along the table areas. The panels 23 and 23' are independently adjustable in a similarity of mounting and cooperate as smooth, coplanar continuations of the table areas 16 and 16' when adjusted into throat-closing engagement of their respective lips 17 and 17' with the cut or edge 22, a mounting and arrangement of said panels effective to accomplish their purposes being illustrated as a hinge rod 24 supported transversely of and beneath the discharge end of the table assembly in and by means of apertured ears 25 fixedly depending from the corresponding ends of the flanges 20, apertured lugs 26 fixedly depending from and adjacent the discharge margins of said panels in engagement with the rod 24, arcuately-slotted ears 27 fixedly depending from the flanges 20 inwardly therewith from the ears 25, a rod 28 transversely of the table assembly between said ears 27 for altitudinal adjustment in the arcuate slots thereof between various clamped engagements therewith, and an apertured lug 29 fixedly depending to engagement with the rod 28 from each of the panels 23 and 23', so that altitudinal adjustment of said rod 28 in the slots of the ears 27 is reflected as vertical arc adjustment of the panels about their common hinge axis and consequent determination of lip 17 and 17' elevation relative to the adjacent table areas 16 and 16'. Manifestly, a separate altitudinally-adjustable rod 28 may be provided for each of the panels, whereby to accommodate individual variation in the throat openings defined by the lips thereof. The table assembly is completed by the provision of suitable means for entrapping, segregating, and

appropriately directing material delivered from the table through the throats established beneath the elevated lips of the panels 23 and 23', and such means is typically illustrated as comprising an outwardly and downwardly inclined trough or launder 18 fixed transversely of and beneath the table to underlie the throat interrupting the table area 16 and to deliver laterally of the table assembly, and a similar trough or launder 18' underlying the throat interrupting the table area 16' for delivery laterally of the table in a direction opposite to that of the element 18.

An operative mounting for the table member is shown as including a pair of like angle members 30 disposed in spacedly-parallel opposition for limited adjustment through vertical arcs about the axes of hinges 31 connecting their corresponding ends with a suitable base, and means engaging between said base and the other ends 15 of the members 30 selectively operable to vary and determine the altitudinal disposition of the member 30 ends thereby supported. The means supporting corresponding ends of the members 30 for altitudinal adjustment may be of any desired 20 appropriate type and construction and are but functionally typified by the illustrated arrangement wherein brackets 32 fixedly upstanding from the base rotatably mount a shaft 33 transversely of and beneath the ends of the members 30 remote from the hinges 31 and eccentrics 34 fixed to said shaft cooperate with eccentric straps 35 fixedly depending from said ends of the members 30, so that rotation of said shaft and the attached eccentrics by any manually-actuatable agency is 25 reflected through the eccentric straps as altitudinal adjustment of the associated member 30 ends, thereby similarly and simultaneously determining the attitude of the members 30 relative to a horizontal plane. Completing an adjustable 30 frame mounting for the table member, like links 36 pivotally upstanding in parallel from and adjacent the ends of each member 30 pivotally engage at their upper ends with and thereby mount an angle bar 37, or equivalent rigid member, spacedly above and parallel to each of the members 30 and length-adjustable braces 38 connect, in oppositely-inclined pairs, between each member 30 and the associated bar 37 to immobilize the latter in any one of the several positions to which it is susceptible of being shifted longitudinally 40 and relative to the associated member 30.

While the table member may be operatively supported by and associated for vibration with the frame just above described through a variety 45 of particular constructions and arrangements, the illustrated organization incorporating and utilizing hydraulic cylinder and piston unit assemblies of conventional type as pulsators is practical and efficient for practice of the improved method. To support the table member on and in the desired operative relation with the adjustable frame represented by the members 30 and bars 37, vertically-paired, like stems 39 are fixed to and outstand perpendicularly from inner faces of the member 30 and bar 37 vertical flanges adjacent the points at which the links 36 pivotally connect with the member and bar. The axis of each said stem 39 lies in the horizontal plane containing the axis of the adjacent link 36 pivotal connection when the member or bar carrying the same is horizontal, and each of said stems 39 hingedly mounts a plate 40 tangent thereto, susceptible of oscillation about the stem axis, and extending inwardly of the assembly beyond the inner end of the associated stem. In-

wardly-extending ends of the plates 40 are apertured to receive and mount a straight, rigid strut 41 which engages through and spans between each vertically-registered pair of said plates in a manner to oppose the engaged plates on adjacent sides of their stems 39. Each strut 41 is thus disposed in spaced parallelism with an adjacent link 36, there being one such strut for each said link, in a strut length and mounting effective to maintain such parallelism in all adjusted positions of the bar 37 relative to the associated member 30. Apertured ears 42 fixedly upstand from the side flanges 20 of the table assembly in a spacing longitudinally thereof corresponding with the spacing between struts 41 on the same side of the frame, and each of said ears carries a plate 43 end-swiveled thereto in a manner to outstand laterally from and parallel to the plane of the table. Each plate 43 is formed with a hole near its inner end adapted to receive and slidably accommodate the appropriate strut 41, so that engagement of said plates 43 with and to slide along the struts 41 serves to mount the table assembly in a generally horizontal disposition within the open area of the frame assembly where it is held against lateral and longitudinal displacement relative to the frame while free to travel altitudinally within the length range of the struts 41 between their mounting plates 40. As so mounted, the table assembly is yieldably supported and retained in a horizontal plane approximately at the midlength of the struts 41 by means of expansive coil springs 44 engaged over and about the strut lengths on each side of the plates 43 in end-bearing engagement between said plates and the plates 40 spacedly opposed thereto, and means, such as a thimble 45 threadedly engaging each plate 40 loosely about the strut end 41 traversing the plate, is provided for varying and adjusting the pressure of the springs 44 in appropriate relation with the table assembly weight and load and to balance and position said assembly in relation to the means employed for its vibration.

Vibratory actuation of the table assembly frame-mounted and arranged as shown and described is feasibly accomplished through the agency of a plurality of like pulsator units 46 of conventional type and construction, each of which is essentially an hydraulic cylinder and piston assembly characterized by a piston stem projection axially through and exteriorly beyond one end of the associated cylinder and means for introducing fluid under pressure to the cylinder at each side of the piston therein. A pulsator unit 46 is fixed at its base to each of the plates 40 with its axis paralleling the adjacent strut 41 and its piston stem projection engaging the adjacent surface of the plate 43, thereby to dispose a pair of said units 46 in axially-aligned opposition on the opposite sides of a plate 43 with the piston stem projections of the units engaged against opposite surfaces of the plate in a relationship operable to oscillate the spring-loaded plate axially of its strut 41 for consequent and corresponding vibration of the table assembly carried by said plates.

The pulsator units 46 are operatively included in a fluid-charged system effective to accomplish their simultaneous, correlated actuation in a manner to develop table assembly vibration of desired amplitude and frequency, one such system being represented by the diagram of Figure 12. A mechanical arrangement for the generation of pulsations of desired amplitude and frequency is

provided and may conveniently take the form of the arrangement shown in Figure 7, wherein a pair of pulsator units 47, the same as or functionally identical with the units 46, is fixedly supported in coaxial alignment and spaced adjacency of their piston stem projections to operatively engage the free end of a pivoted lever 48 interposed between the ends of said stem projections and at approximately right angles to their common axis. An elongated slot 49 longitudinally of the lever 48 slidably accommodates a crank pin 50 carried by and in an adjustable eccentricity on a rotatable disk 51 which is power-driven by any suitable power source, such as an electric motor 52, so that rotation of said disk operates to oscillate the lever 48 on its pivot mounting for repetitive, periodic, and alternate retraction of the pulsator stem projections thereby engaged within their respective cylinders, the frequency of lever 48 oscillation being a function of the speed of disk 51 rotation and the amplitude of such oscillation being a function of crank pin 50 eccentricity, both of which are hence subject to regulation and adjustment. The pulsator units 47 are provided with means for introducing fluid under pressure to, or for permitting escape of fluid from, their cylinders on each side of the associated pistons, and the said means of the units 47 are intercoupled and connected with the like means of the units 46 through an arrangement of pipes or conduits in a manner to transmit piston displacements of the units 47 acting on and through a charge of fluid, such as oil, filling the units 46, 47 and the said pipes or conduits, to effect corresponding displacements of the unit 46 pistons with pulsating reaction against the plates 43 and the table assembly thereby supported. In the illustrated arrangement, a branched conduit 53 connected with the piston side of one unit 47 remote from the lever 48 and the piston side of the other unit 47 adjacent said lever serves, through appropriate branches, the cylinders of all of the units 46 beneath, or on the lower side of their respective pistons, while a similar branched conduit 54 connected with the piston sides of the units 47 not served by the conduit 53 leads through suitable branches to all of the units 46 and connects therewith above or on the upper side of their respective pistons, so that pressure impulses manifest in the conduit 53 as a consequence of unit 47 piston displacement in the appropriate direction through the agency of the lever 48 act to elevate the unit 46 pistons, plates 43, and table assembly, while similar impulses manifest in the conduit 54 as a result of lever 48 oscillation in the opposite direction act to depress the unit 46 pistons, plates 43, and table assembly, thus altitudinally vibrating said table assembly.

With the links 36 and their parallel struts 41 vertical, the table assembly parallel to the members 30, and said latter members horizontal, vibration of the table assembly accomplished through the pulsator system as above described is necessarily vertical and lacking in any horizontal component, the result of such vibration being simply an agitation of the material charge on the table without any charge translation. However, the discharge end of the table may be elevated or lowered through the agency of the means 33-35 for the development of a gravity factor influencing translation of the charge under agitation on the table, and the direction of pulsation application may be varied through adjustment of the braces 38 to shift the bars 37 longi-

tudinally of the members 30 with consequent inclination of the links 36, struts 41, and pulsator unit 46 axes away from the vertical, either or both, thereby to so relate the table inclination and the direction of pulsation application to the material under treatment and the concentration thereof as to develop and maintain material translation from the infeed and to the discharge end of the table during and as an incident of the material agitation and stratification resulting from table assembly vibration.

Use of the apparatus shown and described in and for practice of the improved method should be reasonably apparent from the foregoing. The frame mounting the table assembly having been adjusted to provide the appropriate table inclination and direction of pulsation application, the appropriate pulsation frequency and amplitude having been determined and established through regulations and adjustments characterizing the pulsation-generating means, and the lips 17 and 17' of the adjustable panels 23 and 23' having been set at suitable elevations relative to their adjacent table areas, comminuted ore material delivered through the feeder 15 to the end of the table area 16 remote from the panel 23 is thoroughly and persistently agitated in reaction to table vibration, is caused to travel from the infeed and to the discharge end of the table by virtue of such vibration, is induced to stratify in layers of characteristic particle density as it travels along the table, and is separated as it meets the lip 17 in the course of its travel into a heavier particle fraction diverted through the throat beneath said lip into the launder 18 and a lighter particle fraction which passes over the lip and across the panel 23 to discharge at the end of the table assembly; the heavier particle fraction from the launder 18 similarly reacting when fed to the table area 16' through the feeder 15' and resolving into an enriched heavy particle concentrate diverted beneath the lip 17' to and through the launder 18' and a lighter particle component retained on and for discharge travel across the panel 23'.

Since changes, variations, and modifications in the form, construction, and arrangement of the structural organization shown and described may be had without departing from the spirit of the invention and without deviating from the principles of the method susceptible of practice therethrough, I wish to be understood as being limited solely by the scope of the appended claims, rather than by any details of the illustrative showing and foregoing description.

I claim as my invention:

1. Ore concentrating and separating apparatus comprising a frame adjustable about a transverse horizontal axis, link-supported upper bars in said frame longitudinally shiftable in maintained parallelism with their plane of longitudinal adjustment about said axis, a pair of spacedly-parallel struts pivotally end-connected with each of said upper bars altitudinally of the frame for adjustment relative to the vertical in reaction to longitudinal shift of the associated bar, a mounting block slidably spring-positioned on each of said struts, a table carried by said blocks in maintained parallelism with said upper bars, pulsator units pivotally carried by said frame and engaging said blocks for the synchronous vibra-

tion of the latter axially of their struts in all adjusted strut dispositions, means for infeeding comminuted ore to one end of said table, and an adjustable diversion throat transversely interrupting said table inwardly adjacent its other end.

2. Ore concentrating and separating apparatus comprising spacedly-parallel base frame members simultaneously adjustable about the same transverse horizontal axis, a frame bar pivotally linked to and spaced upwardly from each of said members for longitudinal displacement relative to and in maintained parallelism with the associated member, means for adjusting and securing said bars relative to said members, spacedly-parallel struts pivotally end-engaged with and spanning between each said bar and associated member, mounting blocks slidably spring-positioned on said struts, a table carried by said mounting blocks in maintained parallelism with said base frame members, pulsator units engaging said blocks for synchronous vibration thereof axially of their struts, means for infeeding comminuted ore to one end of said table, and a panel hinged to and transversely interrupting the table end remote from said infeed means altitudinally adjustable to establish a diversion throat from the plane of the table.

3. In ore concentrating and separating apparatus characterized by a frame adjustable about a transverse horizontal axis and a table carried by, adjustable with, and for vibration relative to said frame, a frame mounting of the table selectively adjustable to vary the angle of vibration input to the table while maintaining the table attitude resulting from adjustment of said frame about said axis, said mounting comprising link-supported upper bars in said frame longitudinally shiftable in maintained parallelism with their plane of longitudinal adjustment about said axis, a pair of spacedly-parallel struts pivotally end-connected with each of said upper bars altitudinally of the frame for adjustment relative to the vertical in reaction to longitudinal shift of the associated bar, a mounting block slidably spring-positioned on each of said struts and engaged with said table, pulsator units pivotally carried by said frame and engaging said blocks for the synchronous vibration of the latter axially of their struts in all adjusted strut dispositions, and means for adjustably securing said upper bars in selected positions of longitudinal shift relative to the frame-mounting axis.
